UNITED STATES PATENT OFFICE

VIRGINIA HAMILL, OF NEW YORK, N. Y., ASSIGNOR TO OTIS COMPANY, INC., OF BOSTON, MASSACHUSETTS, A CORPORATION OF MASSACHUSETTS

DESIGN FOR A TEXTILE FABRIC OR SIMILAR ARTICLE

Application filed January 27, 1932. Serial No. 42,642. Term of patent 3½ years.

To all whom it may concern:

Be it known that I, VIRGINIA HAMILL, a citizen of the United States, residing in the borough of Manhattan, city of New York, county of New York, and State of New York, have invented a new, original, and ornamental Design for a Textile Fabric or Similar Article, of which the following is a specification, reference being had to the accompanying drawing, forming part thereof:

The figure is a plan view of a textile fabric or similar article, showing my new design.

I claim:

The ornamental design for a textile fabric or similar article substantially as shown.

VIRGINIA HAMILL.
